UNITED STATES PATENT OFFICE

147,493

DESIGN FOR A COMBINED PERFUME
BOTTLE AND HOLDER

Morris D'Ver, New York, N. Y.

Application May 27, 1946, Serial No. 130,125

Term of patent 3½ years

(Cl. D58—26)

To all whom it may concern:

Be it known that I, Morris D'Ver, a citizen of the United States of America, residing in New York city, county of New York, and State of New York, have invented a new, original, and ornamental Design for a Combined Perfume Bottle and Holder, of which the following is a specification, reference being had to the accompanying drawing, forming part thereof, wherein,

The characteristic features of my new design reside in the portions shown in solid lines.

I claim:

The ornamental design for a combined perfume bottle and holder, substantially as shown and described.

MORRIS D'VER.
